United States Patent

Des. 234,293
Patented Feb. 11, 1975

234,293

BOTTLE OR THE LIKE

Elton Cohen Toland, 691 Irola,
Los Angeles, Calif. 90005

Filed Apr. 2, 1973, Ser. No. 346,733

Term of patent 14 years

Int. Cl. D9—01

U.S. Cl. D9—169

FIG. 1 is a perspective view of a bottle or the like showing my new design;

FIG. 2 is a side elevational view thereof;

FIG. 3 is a top plan view thereof; and,

FIG. 4 is a bottom plan view thereof.

I claim:

The ornamental design for a bottle or the like, substantially as shown.
